DESIGN FOR A PLACE MAT OR SIMILAR ARTICLE

James E. Adair, Chicago, Ill., assignor to The Meyercord Company, Chicago, Ill., a corporation of Illinois

Application October 8, 1948, Serial No. 149,011

Term of patent 14 years

(Cl. D92—26)

To all whom it may concern:

Be it known that I, James E. Adair, a citizen of the United States, residing at Chicago, in the county of Cook, State of Illinois, have invented a new, original, and ornamental Design for a Place Mat or Similar Article, of which the following is a specification, reference being had to the accompanying drawing forming a part thereof, wherein the figure is a plan view of a place mat showing my new design.

I claim:

The ornamental design for a place mat or similar article, substantially as shown.

JAMES E. ADAIR.
